COSMETIC CONTAINER

Charles R. Book, Waterbury, Conn., assignor to
The Eyelet Specialty Company, Waterbury,
Conn.

Application June 20, 1941, Serial No. 398,971

3 Claims. (Cl. 206—56)

This invention relates generally to cosmetic containers and more particularly to such containers in which means are provided for advancing or retracting the cosmetic material longitudinally of the device by the movement of an operating handle longitudinally of the device or by the movement of a cap or similar operating member rotatably about the longitudinal axis of the container.

In cosmetic containers of this type, the principal container is usually in the shape of a cylinder having an operating handle slidably mounted for movement longitudinally of the device or a rotatable cap at one end or the other which when rotated advances the cosmetic material outwardly of the container for use. The propulsion and retraction of the cosmetic material is accomplished by means of a direct action principle or by means of a screw principle. In accordance with such constructions a projection extends outwardly of the cosmetic carrier and is engaged in a straight groove on one hand or spiral groove in conjunction either with a straight groove or another spiral groove having its pitch in the opposite direction on the other hand.

A primary requisite of such devices is that the cosmetic material be moved only when it is positively desired by the user. For example, the container is usually provided with a cap or cover member which closes the open end of the container through which the cosmetic material emerges when in use. With the cover or cap in place in a lady's handbag or in her pocket, if the operating head or other actuating member is accidentally longitudinally moved or rotated, the cosmetic material which is usually a soft cream mass, is forced up against the inner surface of the cover or cap and becomes thereby deformed. Furthermore, a certain amount of the cosmetic material is thus wasted by reason of its adherence to the inner surface of the cover and makes for a generally unkempt and unsatisfactory condition.

As an example of this, it may be noted that when the cosmetic material is in its advanced or projected position, that is, lying outside of the upper part of the container, when the cosmetic is applied a certain amount of pressure is applied longitudinally of the cosmetic stick and the container. This pressure frequently results in the cosmetic material being pushed completely into the container and there is danger that the upper relatively thin edges of the container may damage the lips. Also, when the cosmetic stick moves under normally useful pressure, it becomes difficult to so manipulate the cosmetic stick as to properly place the cosmetic material upon the lips of the user.

While various methods have been proposed to permit more positive control under various con-

ditions of the movement of the cosmetic carrier, some have been open to the objection that they have either been unsatisfactory in operation or they have been too expensive, since in the ordinary commercial use at the present time, when the cosmetic material becomes consumed, the entire container is thrown away. Thus where the container may be efficiently constructed at a lower production cost, the additional savings may be incorporated in improving the quality of the materials in the cosmetic itself.

It is, therefore, one of the principal objects of the present invention to provide a novel and useful cosmetic container in which, by reason of the size, shape and positioning of certain of the parts as well as the organization of the various components, economies both in manufacture of the parts and in the assembly thereof result.

Another object herein lies in the provision of devices of the class described in which the movement of the cosmetic carrier is more positively controlled whereby the same is resiliently frictionally retained in any adjusted position thereof.

These objects and other incidental ends and advantages will more fully appear in the progress of this disclosure and be pointed out in the appended claims.

In the drawings constituting a material part hereof, similar reference characters designate corresponding parts throughout the several views in which:

Figure 1 is an elevational view of an embodiment of the invention. In this figure the position taken by the cover when in its closed position thereof is shown by dot-dash lines.

Figure 2 is an enlarged elevational view partly in section with the cover removed and the cosmetic carrier in the fully advanced or extended position thereof.

Figure 3 is a horizontal sectional view as seen from the plane 3—3 on Figure 2.

Figure 4 is a view in elevation of the cosmetic carrier prior to incorporation with the other components of the device.

Figure 5 is an elevational view as seen from the right side of Figure 4, that is rotated through 90° with relation to Figure 4.

Figure 6 is a horizontal sectional view as seen from the plane 6—6 on Figure 5.

Figure 7 is a fragmentary elevational view of a second embodiment of the invention with the cosmetic carrier in a substantially midway advanced position thereof.

Figure 8 is an elevational view reduced in size taken generally similarly to Figure 7 with the cosmetic carrier in the fully lowered or retracted position thereof.

Figure 9 is a horizontal sectional view as seen from the plane 9—9 on Figure 7.

Turning now to Figures 1 to 6 inclusive showing a first embodiment, in accordance with the invention the cosmetic container generally indicated by numeral 10 comprises a cover 11; an outer cylinder 12; an inner cylinder 13; and a cosmetic carrier 14.

The cover 11 is of inverted cup shape including a cylindrical side wall 15 and a top wall 16 and is preferably in the form of a deep drawn brass shell.

The outer cylinder 12 has both the upper and lower ends 17 and 18 respectively open and is provided with a spiral slot or channel 19. The upper end 20 of the channel 19 is closed and is disposed below the end 17. The lower end 21 of the channel 19 is closed and is disposed adjacent and above the end 18.

The inner cylinder 13 includes the cylindrical side wall 22, the bottom wall 23, and the exposed side wall portion or actuating member 24. The actuating member 24 includes the upper enlargement or shoulder 25 and a lower corresponding shoulder 26. In order to facilitate the rotation of these shoulders together with the parts connected thereto, these shoulders may be knurled in a well known manner. The inner cylinder is thus in the form of an open topped cup having the upper end 27. Slightly below the upper end 27 the inner cylinder 13 is provided with an expanded annular shoulder 28. The inner cylinder 13 is provided with a spiral slot or channel 29 having upper and lower ends 30 and 31 respectively. The lower closed end 31 terminates slightly above the shoulder 25 while the upper end 30 terminates slightly below the shoulder 28. The upper end 30 of the spiral slot or channel 29 is closed except for a vertically directed slot 32 which extends from the end 30 to the edge 27.

The cosmetic carrier 14 is in the form of a hollow cup and is composed of suitable resilient material, preferably spring brass, having a cylindrical side wall 34 and a bottom wall 35. The cup thus opens upwardly, the upper edge of the cylindrical wall 34 being indicated by numeral 36. The side wall 34 is provided with a "V" shaped orifice or cut out 37, thus leaving a resilient tongue or spring member 38 which is formed of the same material as and is integral with the side wall 34. The spring member 38 is of unusual configuration, best seen in Figures 4, 5, and 6 of the accompanying drawings and extends outwardly of the normal body of the cylinder 34 by reason of a bend 39. The bend 39 is along an axis parallel to and spaced from the longitudinal axis of the carrier 14. The outer end of the spring member is provided with an outwardly bent tab-like projection or lug 40, the lug 40 is formed by reason of the bend 41 which is along a line parallel to and spaced from the longitudinal axis of the carrier, thus the lug 40 is normally radially disposed with relation to the longitudinal axis of the carrier 14.

The cosmetic stick 51 may be composed of any suitable material normally used for this purpose and is usually in the form of a solid cylinder. The cosmetic stick 51 has a lower end which is placed in contact with the upper surface of the bottom wall 35 and has an upper end 42. The internal diameter of the carrier 14 is such as to frictionally engage the outer cylindrical wall of the cosmetic stick 51. The internal diameter of the inner cylinder 13 is slightly greater than the external diameter of the carrier 14. The internal diameter of the outer cylinder 12 is slightly

greater than the outer diameter of the inner cylinder 13. The parts thus nest when assembled as best seen in Figure 3.

One method of assembly of the parts to form a complete container is as follows:

The outer cylinder 12 is forced downwardly over the inner cylinder 13 and the upper portion, that is to say, principally the shoulder 28 is contracted in diameter by the forcing together of the opposite vertical sides of the slot 32 so that the outer cylinder 12 may be moved downwardly thereover. Next the carrier is placed within the upper portion of the inner cylinder with the lug 40 in the upper entrance to slot 32. In this position the outer surface of the spring member 38 will frictionally and resiliently engage the inner surface of the inner cylinder 13 adjacent thereto. The width of the slot 32 is normally slightly less than the transverse thickness, that is to say, the distance between the surface 45 and the surface 46 on the lug 40. As the carrier 14 is pushed downwardly, the lug 40 engages the sides of the slot 32 and temporarily forces them out sufficiently to allow the downward passage therebetween of the lug 40. When the lug 40 arrives at a level sufficiently low to have the outer tab thereof engage the inner surface of the outer cylinder 12, the lug 40 will be forced inwardly but by reason of the resilient nature of the spring member 38, this displacement of the lug 40 will be accompanied by no harmful effects. Upon pushing the carrier 14 down farther it will emerge from the slot 32 and into the slot 29. If the outer cylinder is in proper alignment with the inner cylinder, the outer end of the lug 40 will also enter the spiral slot 19. Otherwise, it is merely necessary to rotate the outer cylinder 12 until the slots 19 and 29 intersect at the uppermost portion thereof, at which time the spring member 38 will force the lug 40 outwardly into the slot 19. The cosmetic stick 51 may now be inserted into the carrier 14, though, where desired, the cosmetic stick 51 may have been previously inserted into the carrier 14 before the same was articulately connected with the other parts.

It may thus be seen that rotation of the sleeve or cylinder 12 and/or rotation of the sleeve or cylinder 13 with relation to each other will result in the projection or retraction of the carrier 14 and the cosmetic stick 51. By reason of the construction and configuration of the spring member 38, the same resiliently frictionally engages the inner surface of the cylinder 13 and thus acts as a brake to control the movement of the carrier 14 longitudinally of the device. By adjusting either the resiliency or thickness of the spring member 38 or by adjusting the degree of the bend 39 any desired braking action may be had so that a certain predetermined amount of torque upon either of the cylinders 12 or 13 with relation to each other will be required to cause the carrier to move longitudinally of the device. While the outer cylinder 12 and the inner cylinder 13 have been described as having oppositely pitched spiral slots as is well known in the art to which the present invention relates, obviously either of these slots may be made straight.

While it has been previously stated herein that the width of the slot 32 in the first embodiment of the invention is normally slightly less than the transverse thickness, that is to say, the distance between the surface 45 and the surface 46 on the lug 40, so that the edges of the slot 32 are forced apart while the lug 40 is pushed downwardly between them when inserting the cosmetic

carrier in the device initially, in an alternate construction, the width of the slot 32 may be equal to or slightly greater than the transverse thickness of the lug 40, as above defined. In such construction, the lug 40 will not require any appreciable amount of force in order to push the same through the slot 32 to reach the slot 29. After the lug 40 has engaged not only the slot 29 but also the slot 19 which, as seen in Figure 1, has a closed upper end as indicated by numeral 20, this closed upper end of the slot 19 will prevent inadvertent removal of the cosmetic carrier since the lug 40 will be prevented from entering the slot 32 by the portion 20 of the slot 19.

Since all of the parts are each capable of being fabricated independently from all of the others and no machine forming or distorting operations are required at the time of assembly, both the cost of fabrication and assembly is reduced. It may be noted, however, that by use of the integral lug 40, the need for punching the carrier 14 and providing the same with a riveted projection is eliminated. Since the lug 40 is resiliently mounted, the same may shift radially of the device as the carrier is longitudinally shifted in either direction to accommodate slight variations in the size of the parts so that the commercial tolerances required during the manufacturing operations may be so much greater.

By reason of the novel braking action obtained by the use of the spring member 38, accidental or indefinite moving of the carrier, either up or down, during use or during the carrying thereof is reduced to a minimum.

Turning now to the second embodiment of the invention illustrated in Figures 7 to 9 inclusive for the purpose of avoiding needless repetition, parts corresponding generally to those of the first embodiment are given singly primed reference characters.

The principal difference between the second embodiment and the first embodiment lies in the fact that instead of the cosmetic carrier 14' being elevated by means of cooperating spiral slots or a spiral slot and a straight slot, the cosmetic carrier is elevated by a manual operation by elevating the actuating member 24" in a rectilinear direction along the straight slot 29". The ends 30" and 31" act as limits for the movement of the lug 40' longitudinally of the device 10'.

In the second embodiment the distance between the sides of the slot 32' is not only less than the thickness of the lug 40', that is to say, between the surfaces 45' and 46' so that after being once installed, the lug 40' may not enter the slot 32' so that the end 30" of the slot 29" may serve as a suitable upper limit.

As previously described in connection with the first embodiment, the resilient tongue or spring member 38' engages the inner surface of the cylindrical side wall 22' of the cylinder 13' and thereby acts as a brake to prevent undesirable longitudinal shifting of the cosmetic carrier 14' with relation to said cylinder.

It may be noted at this point, that in all of the constructions described the cosmetic carrier 14' is of substantially identical construction so that the same may be interchangeable used in the different general types of device.

I wish it to be understood that I do not desire to be limited to the exact details of construction shown and described for obvious modifications will occur to a person skilled in the art.

I claim:

1. A cosmetic container comprising, an outer cylinder having a first slot, an inner cylinder disposed within the outer cylinder and having a second slot, one of said slots being angularly disposed with relation to the other, a cosmetic carrier having an external diameter less than the internal diameter of the inner cylinder, said carrier being in the form of a hollow cup and composed of resilient material and having a cylindrical side wall and a bottom wall, said side wall being provided with a substantially V-shaped cut-out thereby forming a spring member integral with said side wall, said spring member being outwardly bent along an axis parallel to and spaced from the longitudinal axis of the carrier, said spring member extending outwardly of the normal body limits of the said side wall and adapted to resiliently frictionally engage the inner surface of the inner cylinder, the outer free end of the spring member being outwardly bent along a line parallel to and spaced from the longitudinal axis of the carrier, forming an outwardly bent tab-like lug which is normally radially disposed with relation to the longitudinal axis of the carrier, said lug penetrating the first and second slots, whereby rotational displacement of one of said cylinders with relation to the other will cause a displacement of said carrier longitudinally of the cosmetic container, said spring member acting to frictionally retain the carrier in displaced position thereof.
2. A cosmetic container comprising, an outer cylinder having a first helical slot angularly disposed with relation to the central longitudinal axis of said container, an inner cylinder disposed within the outer cylinder, said inner cylinder having a second helical slot angularly disposed with relation to the first slot, a cosmetic carrier of cup form having an external diameter less than the internal diameter of said inner cylinder, said carrier having an integrally formed resilient member consisting of an outwardly bent free end tongue constituting a part of the side wall of the carrier, said resilient member being normally disposed outwardly of the body of the carrier and adapted to resiliently engage the inner surface of the inner cylinder, said resilient member having an outwardly extending bent free end forming a lug penetrating the first and second slots, whereby rotational displacement of one of said cylinders with relation to the other will cause a displacement of the carrier longitudinally of the cosmetic container, said resilient member acting to frictionally retain the carrier in a displaced position thereof.
3. In a cosmetic container, a pair of concentrically disposed cylinders, one of said cylinders being rotative within the other, each cylinder having a slot disposed angularly to the slot of its companion, a cup-shaped cosmetic carrier within the inner cylinder and arranged for longitudinal movement therein, the side wall of the cosmetic carrier having a laterally bent integral spring tongue frictionally engaging the inner surface of the inner cylinder, said tongue having a single free end bent to provide a lug entrant into both slots, whereby rotative movement of one cylinder relative to the other will cause a displacement of the carrier longitudinally of the container.

CHARLES R. BOOK.
